UNITED STATES PATENT OFFICE.

FRANZ MURKE, OF FORT COLLINS, COLORADO.

PROCESS OF REFINING RAW CANE-SUGAR.

1,132,868.

Specification of Letters Patent. Patented Mar. 23, 1915.

No Drawing.

Application filed June 20, 1914. Serial No. 846,403.

To all whom it may concern:

Be it known that I, FRANZ MURKE, a citizen of the United States, residing at Fort Collins, in the county of Larimer and State of Colorado, have invented new and useful Improvements in Processes of Refining Raw Cane-Sugar, of which the following is a specification.

My invention relates to the refining of sugar, and particularly to the refining of raw cane sugar.

It is well known that raw cane sugar consists of sugar crystals which are surrounded by molasses, a syrup containing considerable amounts of glucose or invert sugar, besides other impurities. In the treatment of the raw sugar by the hot lime process, the sugar is boiled with sufficient lime to eliminate the glucose, but while the glucose is destroyed as such, there are lime salts formed which are molasses forming.

The syrup surrounding the sugar crystals and containing the glucose may be eliminated by washing with wash syrups, or water, or steam, until the sugar is free from glucose, but the washed sugar crystals thus obtained contain coloring materials which penetrate the sugar crystals and can not be washed away. Inasmuch as the thoroughly washed cane sugar can not be made whiter by further washing, I proceed to destroy or change the coloring materials by boiling the solution of the well washed raw cane sugar with lime to such a degree that, after precipitating the lime by carbonic acid and sulfuric acid, or sulfuric acid alone, with the necessary filtrations, the resulting fillmass turns out a perfectly white sugar.

A decided chemical reaction may be observed during the process of boiling the washed raw cane sugar solution with lime, gas and foam being formed. This reaction lasts about three to five minutes until the changing or conversion of the coloring material is completed and the juice comes to a quiet and clear boiling, like ordinary solutions of refined sugar will show in boiling.

My process, as above outlined, is preferably carried out as follows: High grade raw cane sugar is mixed with molasses to a magma, which is then spun in centrifugal machines and the sugar washed with water or other suitable agent in order to remove the glucose and other impurities surrounding the sugar crystals. By the term "other suitable agent" it is understood that the washing

medium may be wash syrup, water, steam, or any other of the well known agents or that the separation of the sugar crystals and surrounding syrup can be effected by the application of heated and compressed air or superheated steam with little or no wash syrup resulting from their use. The well washed or cleaned sugar is then melted in water and sweet water from the carbonation and sulfitation filter press stations to thick juice consistency. This solution is pumped through filters or directly to vertical, cylindrical open tanks provided with heating coils and stirrers. Lime is then added, preferably in the form of milk of lime, in the proportion of one-half per cent. or less to two per cent. of the sugar present. The temperature is raised to boiling and the boiling continued until the gas and foam formation ceases and the liquor comes to a quiet and clear boiling. These tanks are advantageously erected on a sheet iron floor to catch losses from boiling over, and are best and safest operated from above. From these tanks the juice is pumped to an intermittent or continuous carbonation station where it is treated with carbonic acid to an alkalinity of about 0.100 per cent., then filtered and saturated with sulfuric acid gas (SO_2) to slight alkalinity, and filtered again. The temperature is not allowed to fall below 80° C. Soda ash may be added before the final filtration. The liquor is then boiled to fillmass, etc. The treatment described in this paragraph is well known and may be varied without departing from my invention. Part of the molasses which results from the mixing and washing process is used for mixing the next raw sugar, and part leaves the process as "rest molasses." The molasses which results from the process after the lime treatment and crystallization which contains little or no trace of glucose is also used for mixing the high grade raw cane sugar and serves by its application to reduce the glucose content of the resulting magma to the lowest possible degree.

The wash syrup is made neutral with lime, if it is not so already, and is either boiled by itself to high grade raw sugar which is treated as above, or such low grade raw cane sugar which does not stand much washing on account of its soft grain is melted in the wash syrup and water, made neutral if not so already, and boiled to high grade raw cane sugar which is treated as above.

From the above it will be understood that my process results in a considerable economy of time and materials, doing away with the bone black filtration and furnishes a product comparatively pure and free from certain salts and other impurities which are present in the products of other processes. The removal of the glucose and other soluble impurities by washing before the lime treatment prevents the formation of undesirable salts which would result from the action of the lime on the glucose, etc.; and by following the washing by lime treatment and other refining steps the coloring matter and other impurities which remain are eliminated.

The process permits the manufacture of beet sugar to be combined with the refining of raw cane sugar, using the machinery of the beet sugar houses.

It will also be understood that various modifications of my process as above described may be made without departing from the invention. For instance, various materials and reagents may be employed as equivalents or substitutes for those mentioned, and all such I regard as falling within the scope of my invention.

Having described my invention, what I claim as new and desire to secure by Letters Patent of the United States, is—

1. The process of refining raw cane sugar, which process comprises removing without chemical change impurities of the syrup surrounding the sugar crystals, and treating at substantially boiling temperature a solution of the resulting crystals with a reagent acting to change the impurities originally included in the sugar crystals to material which will be excluded from the crystals upon recrystallization.

2. The process of refining raw cane sugar, which process comprises removing without chemical change impurities of the syrup surrounding the sugar crystals, and treating at substantially boiling temperature a solution of the resulting crystals with lime or its equivalent to change the impurities originally included in the sugar crystals to a material which will be excluded from the crystals upon recrystallization.

3. The process of refining raw cane sugar, which process comprises removing without chemical change impurities of the syrup surrounding the sugar crystals, treating at substantially boiling temperature a solution of the resulting crystals with lime or its equivalent to change the character of the impurities originally included in the sugar crystals, and recrystallizing the sugar from the solution to the exclusion of the changed impurities from the crystals.

4. The process of refining raw sugar, which process comprises mechanically removing from the sugar impurities of the syrup sur-

rounding the sugar crystals, and treating at substantially boiling temperature a solution of the resulting crystals with lime or its equivalent.

5. The process of refining raw sugar, which process comprises washing the sugar to remove glucose and other impurities of the syrup surrounding the sugar crystals, making a solution of the washed crystals, and acting upon the coloring impurities of said solution by treating said solution at substantially boiling temperature with lime or its equivalent.

6. The process of refining raw sugar, which process comprises washing the sugar to remove impurities of the syrup surrounding the sugar crystals, and then treating at substantially a boiling temperature a solution of the washed crystals with lime or its equivalent.

7. The process of refining raw cane sugar, which process comprises washing the sugar to remove glucose and other impurities of the syrup surrounding the sugar crystals, making a solution of the washed crystals, and treating said solution at substantially the boiling temperature with lime or its equivalent.

8. The process of refining raw cane sugar, which process comprises washing the sugar to remove glucose and other impurities of the syrup surrounding the sugar crystals, making a solution of the washed crystals, and boiling said solution with lime or its equivalent until the gas and foam formation ceases, and the solution comes to a quiet and clear boil.

9. The process of refining raw cane sugar, which process comprises washing the sugar to remove glucose and other impurities of the syrup surrounding the sugar crystals, making a solution of the washed crystals, treating said solution at substantially the boiling temperature with lime or its equivalent, precipitating the lime, and further purifying or refining the sugar.

10. The process of refining raw cane sugar, which process comprises washing the sugar to remove glucose and other impurities surrounding the sugar crystals, melting the washed crystals in water and sweet water from carbonation and sulfitation filter press stations to thick juice consistency, and treating this solution at boiling temperature with lime or its equivalent.

11. The process of refining raw cane sugar, which process comprises washing the sugar to remove glucose and other impurities surrounding the sugar crystals, and boiling a solution of the washed crystals at thick juice consistency with a small amount of lime to destroy or convert into harmless form for the crystallization of white sugar those impurities including coloring material which cannot be eliminated by washing.

12. The process of refining raw cane sugar, which process comprises washing the sugar to remove glucose and other impurities surrounding the sugar crystals, boiling 5 a solution of the washed crystals at thick juice consistency with a small amount of lime, and submitting said solution subsequently to ordinary refining processes as used in beet sugar factories, such as saturation with carbonic acid and sulfurous acid 10 gas or sulfurous acid gas alone with the necessary filtrations and other ordinary beet sugar house refining processes.
13. The process of refining raw cane sugar, which process comprises removing the glucose and other impurities of the syrup surrounding the sugar crystals by washing with wash syrup, making a solution 15 of the cleaned crystals, and treating said solution at substantially the boiling temperature with lime or its equivalent.
14. The process of refining raw cane sugar, which process comprises washing the sugar with steam to remove glucose and 20 other impurities of the syrup surrounding the sugar crystals, making a solution of the cleaned crystals, and treating said solu- 25
- tion at substantially the boiling temperature with lime or its equivalent.
15. The process of refining raw cane sugar, which process comprises removing the glucose and other impurities of the syrup surrounding the sugar crystals by blowing out with superheated steam to effect a mechanical separation of the sugar crystals 30 and surrounding syrup, making a solution of the cleaned crystals, and treating said solution at substantially the boiling temperature with lime or its equivalent.
16. The process of refining raw cane sugar, which process comprises removing the glucose and other impurities of the syrup surrounding the sugar crystals by blowing out with heated compressed air, making a 35 solution of the cleaned crystals, and treating said solution at substantially the boiling temperature with lime or its equivalent.

In testimony whereof I affix my signature in presence of two witnesses.

FRANZ MURKE.

Witnesses:

A. L. ROBLING,
O. A. HILLER.

It is hereby certified that in Letters Patent No. 1,132,868, granted March 23, 1915, upon the application of Franz Murke, of Fort Collins, Colorado, for an improvement in "Processes of Refining Raw Cane-Sugar," an error appears in the printed specification requiring correction as follows: Page 1, line 80, the matter beginning with the word "From" to and including the word "invention," same page, line 93, should form a separate paragraph; and that the said Letters Patent should be read with this correction therein that the same may conform to the record of the case in the Patent Office.

Signed and sealed this 27th day of April, A. D., 1915.

[SEAL.]

J. T. NEWTON,

Acting Commissioner of Patents.
